INVENTOR—
John E. Sweet
for Bradley Laasch & Heng

UNITED STATES PATENT OFFICE.

JOHN E. SWEET, OF SYRACUSE, NEW YORK.

JOURNAL-BOX.

SPECIFICATION forming part of Letters Patent No. 309,582, dated December 23, 1884.

Application filed May 22, 1884. (No model.)

To all whom it may concern:

Be it known that I, JOHN E. SWEET, of Syracuse, in the county of Onondaga, in the State of New York, have invented new and useful Improvements in Journal-Boxes, of which the following, taken in connection with the accompanying drawings, is a full, clear, and exact description.

This invention consists in a novel construction of a solid journal-box having bearings which are easily adjusted to compensate for the wear thereof, and thus prevent pounding of the same without danger of producing undue binding and friction thereon, and which, furthermore, are readily renewed at very little expense.

The invention is fully illustrated in the annexed drawings, wherein Figure 1 is an end view of my improved journal-box. Fig. 2 is a longitudinal section thereof. Figs. 3 and 4 are respectively a longitudinal and a transverse section of the solid box. Figs. 5 and 6 represent, respectively, a side view and a transverse section of one of the cheek-pieces; and Figs. 7, 8, and 9 are plan, edge, and end views of the key or wedge which is employed between the thick edges of the cheek-pieces.

Similar letters of reference indicate corresponding parts.

30 A represents the solid box, in the form of a cylindrical shell having an eccentric circular bore.

B B denote cheek-pieces having segmental inner and outer faces, the latter of which corresponds to the concavity of the shell A, and the inner face is eccentric to the outer face. Said cheek-pieces are applied to the interior or bore of the solid shell A, with the thick portion of the former on the thin portion of the 40 said shell, so as to bring the inner faces of the cheek-pieces concentric with the exterior of the external shell, A, and thus maintain the shaft in line. The interior of the thick or bottom portion of the shell A is provided in its center with a longitudinal spline or feather, e, against which the thin edges of the cheek-pieces B B abut, the latter being thus maintained uniformly distributed on opposite sides of the journal-box, which feature is very essential, inasmuch as it serves to maintain the interior of the cheek-pieces in concentricity

with the shaft, and prevents either of the cheek-pieces from crowding against the side of the shaft. Between the adjacent thick edges of the cheek-pieces is inserted a key or wedge, 55 D, by means of which the cheek-pieces are held firmly seated on the spline e. Between the spline and adjacent thin edges of the cheek-pieces are interposed liners a a, of type-metal or other suitable material, and when the cheek-pieces become worn by the friction of the shaft revolving thereon a sufficient number of the liners are removed from their aforesaid position and placed by the side of the wedge D, to cause the cheek-pieces to move toward the bottom of the box, and thereby take up the play 60 and become properly seated to prevent pounding of the bearings on the shaft. By proper care of the aforesaid adjustment all danger of the bearings of the cheek-pieces becoming unduly bound or tightened on the shaft, so as to cause 65 the parts to become heated by friction, is obviated. After all the liners have been shifted, as aforesaid, strips of considerable width can be cut from the lower edges of the cheek-pieces, 70 and other liners introduced at the sides of the spline, so as to get additional wear out of the cheek-pieces. 75

E represents a lubricating-ring employed to return the oil from the drip-pocket to the top of the shaft, the operation thereof being well understood and needs no detail description in this case.

It will be observed that by the described construction and combination of parts I obtain 85 a solid box, which cannot give way or get loose, and is devoid of joints for the escape of the lubricant either at the bottom or sides.

Having described my invention, what I claim as new, and desire to secure by Letters Patent, is—

1. A journal-box comprising a solid shell having a circular bore, and eccentric cheek-pieces applied to the said bore, substantially as described and shown.

2. A journal-box composed of an external solid cylindrical shell having an eccentric circular bore, and internal cheek-pieces having segmental inner and outer faces eccentric in relation to each other, and placed with their thick portion on the thin portion of the aforesaid shell, substantially as shown and set forth.

3. A journal-box comprising a solid shell having a central bore, a spline on the bottom portion of said bore, and eccentric cheek-pieces applied to the said bore, and sustained by their 5 abutment on the spline, substantially as specified.

4. In a journal-box, the combination of a solid shell having a circular bore, eccentric cheek-pieces applied to said bore, a wedge or 10 key inserted between the thick edges of the cheek-pieces, and liners removably interposed between the adjacent thin edges of the cheek-pieces, substantially as described.

5. In a journal-box, the combination of a 15 solid shell having a circular bore, eccentric cheek-pieces applied to said bore, a spline or feather secured to said shell between the thin edges of the cheek-pieces, and liners removably inserted between the aforesaid feather 20 and adjacent edges of the cheek-pieces, substantially as shown and set forth.

6. In a journal-box, the combination of a solid shell having a circular bore, eccentric cheek-pieces applied to said bore, a spline in the bottom portion of the bore, liners interposed between said spline and thin edges of the cheek-pieces, and a wedge inserted between the thick edges of the cheek-pieces, all constructed and combined substantially in the manner specified and shown. 25

In testimony whereof I have hereunto signed my name and affixed my seal, in the presence of two attesting witnesses, at Syracuse, in the county of Onondaga, in the State of New York, this 15th day of May, 1884. 30

JOHN E. SWEET. [L. S.]

Witnesses:

C. BENDIXEN,
